UNITED STATES PATENT OFFICE.

WILLIAM J. CARTER AND GEORGE J. HOLMES, OF CHICAGO, ILLINOIS.

DESIGN FOR A NECKTIE.

SPECIFICATION forming part of Design No. 29,911, dated December 27, 1898.

Application filed December 5, 1898. Serial No. 698,374. Term of patent 3½ years.

To all whom it may concern:

Be it known that we, WILLIAM J. CARTER and GEORGE J. HOLMES, citizens of the United States, residing at Chicago, in the county of Cook and State of Illinois, have invented and produced a new and original Design for Neckties, of which the following is a specification.

The accompanying drawing is a view in elevation of a necktie of the kind commonly known as a "puff-scarf" presenting our design.

A is the necktie proper, B the material of which it is formed, and C pin-heads, beads, or buttons near the top of the tie.

The leading feature of our design consists in a necktie of the kind commonly known as

a "puff-scarf," having the material of which it is formed so shaped, plaited, and folded as to present in general outline the head, beak, and body of an owl and having two pin-heads, 20 beads, or buttons a slight distance below its top, one at each side of its longitudinal center, presenting the appearance of owls' eyes.

We claim—

The design for a necktie herein shown and 25 described.

WILLIAM J. CARTER.
GEORGE J. HOLMES.
